Primary Examiner — George D Kirschbaum*Assistant Examiner* — Jennifer Watkins(57) **CLAIM**

The ornamental design for a license plate bronc noseband, as shown and described.

DESCRIPTION

FIG. 1 is a perspective front view of a license plate bronc noseband, shown on a horse halter;

FIG. 2 is a perspective front elevation view of the license plate bronc noseband;

FIG. 3 is a front elevation view of the license plate bronc noseband;

FIG. 4 is a rear elevation view of the license plate bronc noseband;

FIG. 5 is a left side elevation view of the license plate bronc noseband, right side elevation view is a mirror image thereof; and,

FIG. 6 is a top plan view of the license plate bronc noseband, bottom plan view is a mirror image thereof.

The horse, halter and rivets shown in broken line are for the purpose of illustrating environment that forms no part of the claimed design. The broken line showing on the license plate bronc noseband illustrates portions of the article that forms no part of the claimed design.
